UNITED STATES PATENT OFFICE.

SOLOMON W. BATES AND ANDREW F. SANBORN, JR., OF PORTLAND,
MAINE.

PENCIL-SHARPENER.

SPECIFICATION forming part of Letters Patent No. 761,191, dated May 31, 1904.

Application filed June 29, 1903. Serial No. 163,536. (No model.)

To all whom it may concern:

Be it known that we, SOLOMON W. BATES and ANDREW F. SANBORN, Jr., citizens of the United States of America, and residents of 5 Portland, Cumberland county, and State of Maine, have invented certain new and useful Improvements in Pencil-Sharpener, of which the following is a specification.

Our invention relates to pencil-sharpener 10 of that class wherein the knife of a conical cutter is used to cut the wood from the point, leaving the lead uncut, the lead being subsequently ground off with abrasive material which forms part of the sharpener.

15 The invention consists of a conical cutter having the flat portion of the knife formed into a file, so that the file which is used for grinding off the point performs two functions, acting at the same time as a knife and 20 a file.

It further consists in forming the knife-edge of the file obliquely with relation to the sides, so that a narrow file can be made with 25 sufficient length of cutting edge to give the desired taper to the pencil.

We illustrate our invention by means of the accompanying drawings, in which—

Figure 1 is a plan view. Fig. 2 is a side elevation. Fig. 3 is a section on the line xx of Fig. 2, and Fig. 4 is a section on the line yy of Fig. 1. Fig. 5 shows a modification.

A represents a suitable base, preferably of wood, formed with a handle a . It is provided with a transverse conical hole d , having the 35 taper desired for the pencil. A slot a^2 is cut through the wood into the top of this conical hole, and an inclined surface is formed adjacent to the conical hole, on which is secured the cutting-knife in the usual manner of con-

40 structing such conical sharpeners. The knife b is formed on the end of the file B , and the file is secured to the base by screws b passing through oblong slots in the file. The conical hole has its smaller end preferably 45 left large enough so that the knife as it cuts leaves a portion of wood surrounding the lead. The pencil is first inserted in the conical cutter and the wood cut away sufficiently far, leaving the lead uncut. The latter is

then ground off on the file and the point thus 50 formed.

It will be seen that according to our invention the file performs the double function of a knife and a file, and thus simplifies the construction of the device. It has the further 55 advantage of forming the knife with sufficient size so that it can be easily taken off and handled for the purpose of sharpening, whereas a very small knife, such as is generally used, cannot be easily handled and few people will take the trouble to sharpen them when they once get dull.

In Fig. 5 is shown a modification in which the knife is formed obliquely to the edges of the file, so as to give the necessary length of 65 cut to form the desired taper to the pencil. In this figure, A' is the base, and B' the file. When the cutting edge is thus formed obliquely across the end of the file, a narrow file may be used, while giving the necessary 70 length to the cutting edge of the knife.

We claim—

1. The herein-described pencil-sharpener consisting of a block formed with a handle at one end and a transverse conical opening 75 formed at the base of said handle, said block having an elongated surface substantially tangent to said conical opening and extending toward the end opposite to the said handle, a file having transverse serrations and provided 80 with a cutting edge upon one end, said cutting edge being adjacent to the conical opening, said file being further provided with slots through the body thereof, and screws passing through said slots of the file and into the block 85 for securing the file adjustably upon the block.

2. The herein-described pencil-sharpener consisting of an elongated block having a transverse conical opening therein, the axis of which is oblique to the sides of said block, an elongated flat file secured to said block having a knife formed on its end, the cutting edge of said knife being substantially parallel with the axis of said conical opening and forming with said conical opening, a conical cutter. 90

3. The herein-described pencil-sharpener consisting of a longitudinal block provided with a handle at one end, a transverse conical

opening formed at the base of the handle near the upper surface of the block so as to present a transverse slot in the upper face of the block, a file having transverse serrations and provided with a cutting edge upon one end adjustably secured upon the upper face of the block so that the cutting edge projects slightly into the slot formed by the conical opening, and means for adjustably securing the file to the block.

10 4. The herein-described pencil-sharpener, consisting of a longitudinal block provided at one end with a handle and with transverse conical bore formed in the body of the block at the base of the handle so as to provide a trans-

15 verse slot in the upper surface of the block, a file provided with a cutting edge upon one

end, central serrations, and longitudinal slots through the body thereof near its ends beyond the serrations, said cutting edge being adapted to project into the slot and slightly beyond the inner surface of the conical bore, and screws adapted to pass through said slots of the file and adjustably secure the file upon the block.

Signed at Portland, Maine, this 26th day of 25 June, 1903.

SOLOMON W. BATES.
ANDREW F. SANBORN, JR.
